UNITED STATES PATENT OFFICE

2,621,089

RAILWAY JOURNAL LUBRICATOR

James J. Hennessy, Chambersburg, Pa., assignor
to Hennessy Lubricator Company, Inc., Cham-
bersburg, Pa., a corporation of Delaware

Application July 27, 1949, Serial No. 107,100

5 Claims. (Cl. 308—84)

1

The invention relates to mechanical lubricators of the type particularly adapted for use in railway journal boxes and including a distributor engaging the journal and a mechanical pump for supplying lubricant to the distributor and actuated by the play of the journal in the journal box longitudinally of the journal.

One of the problems attending the use of such lubricators in boxes such as are in general use is the difficulty of inserting and removing the lubricator pump and distributor through the open end of the box and beneath the journal. The restricted space between the bottom of the journal and the bottom of the box usually requires that the box be jacked up from the journal, the journal bearing and wedge removed, and the box lowered directly onto the journal before the pump can be applied or removed.

The main object of the present invention is to facilitate the insertion and removal of the pump and distributor into and from the space beneath the journal while the journal is in the journal box and without removing the wedge and journal bearing.

Another object is to readily and securely position the pump in the box, when the pump is in operating position, without affecting removability of the pump when desired.

In some earlier arrangements, as in applicant's Patent No. 2,331,835, issued October 12, 1943, having the same general objects, the distributor, after being inserted in the journal box and before the pump is inserted, has the lower end of a pump-engaging conduit arm resting on the bottom of the box and a spring compressed between the arm and the body of the distributor supports the distributor proper against the journal. As the pump is inserted in the journal beneath the distributor, the distributor arm must be raised above the bottom of the box against the tension of the spring so that the pump can be inserted below the distributor arm.

It is an additional object of the present invention to hold the distributor conduit arm spaced from the bottom of the box before the pump is inserted so that the pump may be readily inserted in position below the distributor. In the embodiment shown, this is accomplished by providing a pump holding plate on the bottom of the box with an upstanding rib for engaging the distributor at points spaced from its conduit arm.

Another object is to hold the distributor conduit arm against movement inwardly of the box as the pump is being inserted and to disen-

gage the distributor conduit arm from the pump as the pump is being removed.

These general objects and other detail objects, as will be described below, are attained by the structure illustrated in the accompanying drawings, in which

Figure 1 is a longitudinal vertical section through a journal box taken approximately on the line 1—1 of Figure 2 and showing a lubricator device constructed according to the invention.

Figure 2 is a transverse vertical section through the journal box, the left-hand side being taken approximately on the line 2—2 of Figure 1 and the right-hand side being taken approximately on the line 2a—2a of Figure 1.

Figure 3 is a top view of the lubricator device with the distributor removed.

Figure 4 is a detail view corresponding generally to Figure 1 and drawn to an enlarged scale and illustrates the manner of applying and removing the pump to and from the journal.

Figure 5 is a detail section taken on the line 5—5 of Figure 4 but with the parts in the position shown in broken lines in Figure 4.

A collarless journal 1 mounts the bearing 2 and wedge 3 upon which the box 4 is carried. The latter has upright side walls 5 and a bottom wall 6. The front end of the box has the usual opening 7 provided with a door (not shown) and the rear wall 8 of the box has the usual opening 8a for receiving the journal and is equipped with a suitable dust guard 8b. A drain 6a, substantially as described in Patent No. 2,353,467, issued to the present inventor July 11, 1944, may be provided in bottom wall 6 of the box. All of the above elements are of familiar construction and in themselves do not constitute the present invention.

The lubricator consists generally of two parts, a pump 10 and a distributor 11. The pump may be of the type disclosed in applicant's earlier Patent No. 2,331,835, and includes reciprocating pistons 12, actuated through levers 13 by the play of the axle and journal longitudinally of the box, to take oil from the bottom of the box into cylinders in pump body 14 from which the oil is discharged to a cup-like recess 15 in which is seated the spherical lower end 16 of a conduit arm 17 of the distributor. In the present arrangement, the upper surface 14a at the rear end of the pump body is inclined upwardly and forwardly to facilitate inserting the pump body below the lower end of conduit arm 17.

The distributor has a plurality of Celotex pads

18 and plywood sections 19 seated in pans 20, 21, 22 which are hinged to one another to swing vertically to facilitate application and removal of the distributor to and from the journal through opening 7. Conduit arm 17 is hinged at its upper end to the bottom of pan 20 and at its lower end rigidly mounts a transverse element 23 provided with spaced members 24 for the purpose described below. Spaced compression springs 25, seated on element 23 and the bottom of pan 21, urge pads 18 and sections 19 upwardly into engagement with the journal. Lubricant is pumped from an oil supply in the lower portion of the box through conduit 17 to the pads 18 and sections 19 and is distributed by the pads and sections to the surface of the journal.

The pump, distributor and associated structure are positioned in the box by a removable holding plate 26, the sides of which are channel sectioned (Figure 2) with the down-turned flanges 26a resting on the bottom of the box. The plate has a deep recess extending inwardly from its forward end and receiving the pump body 14. Lateral recesses 27 in the plate receive lugs 28 on the pump body. Plate 26 is positioned by a retainer 29 at each side of the box having a down-turned flange 29a, the forward end 29b of which is bent at right angles and opposes the forward end of an adjacent leg of plate 26. Retainers 29 are welded to the box side wall at W and to the box floor at W'.

An upstanding rib 36 is welded onto each leg of holding plate 26. The top edge of the rib has an irregular contour which slopes upwardly and rearwardly at 36a from its forward end to a high point 37, then slopes downwardly and rearwardly at 36b and then extends horizontally at 39 to a forwardly facing shoulder 38. When the pump is in the position shown in Figure 1 with terminal 16 seated on the pump, transverse element 23 extends over sections 39 but is spaced above the same.

The lubricator is assembled to the box and journal as follows:

Retainers 29 are welded to side wall 4 and to bottom wall 6 of the box. Holding plate 26 is placed between retainers 29 and behind flanges 29b. Distributor 11 is inserted through box opening 7 and beneath the journal, elements 24 being placed between ribs 36 to hold the distributor against twisting. During movement rearwardly of the box, element 23 rides up inclines 36a, compressing springs 25 and moves over projections 37 and down inclines 36b and rests on horizontal portions 39 (Figure 4). Shoulders 38 will limit the rearward movement of the distributor.

Pump 10 is then inserted through box opening 7, first assuming the position indicated in broken lines in Figure 4. Further inward movement of the pump causes the upwardly facing inclined surface 14a on the liner end of the pump to engage conduit terminal 16 and the latter rides up surface 14a and seats in recess 15 in pump body 14 as indicated in Figure 1. The pump body lugs 28 are dropped into recesses 27 and the parts are in position to function. The pump and distributor will be held against movement longitudinally of the box and the reciprocation of the journal will actuate the pump levers 13 to cause the pump to elevate oil through the distributor to the journal.

When the pump and distributor are to be removed, the operator simply pulls on the pump and terminal 16, transverse element 23 and the dis-

tributor slide to the left and element 23 rides up incline 36b until it rests on projection 37, as indicated in broken lines in Figure 4. Then the pump is freed from terminal 16 and may be lifted and readily withdrawn from the box. After the pump is removed, the distributor may be removed by pulling outwardly on the same, member 23 riding down incline 36a.

A lubricator device of the kind described may be readily installed in and removed from the space beneath the journal while the journal is in the journal box and without removing the wedge and journal bearing. The lower end of the distributor conduit is spaced from the bottom of the box and from the pump-holding plate before the pump is installed so that the pump body may be readily inserted between the holding plate and distributor. The holding plate positions the pump securely in the box.

The details of the construction may be varied substantially without departing from the spirit of the invention and the exclusive use of those modifications coming within the scope of the claims is contemplated.

What is claimed is:

1. In a journal lubricator for a railway vehicle journal box, a distributor having a portion for engaging a journal, a downwardly inclined conduit hinged at its upper end to said portion, an elongated element on and extending transversely of the lower end of said conduit, and springs seated on the ends of said element and urging said portion away from said element, a pump including a body having a portion between said springs receiving the lower end of said conduit, a horizontally disposed plate having a recess receiving the pump body, spaced upstanding ribs on said plate extending lengthwise thereof and engaging the ends of said element when the pump is removed and thereby spacing the lower end of the conduit from the plate and so that the pump body may be readily inserted below the lower end of the conduit.

2. In a journal lubricator for a railway vehicle journal box, a distributor having a body with an upper face concaved for engaging a journal, an elongated conduit extending longitudinally of the concavity of said face and hinged at its upper end to said body and inclined downwardly therefrom, a member on the lower end of said conduit extending transversely thereof, a spring thrusting said member and body away from each other, a pump including a body having an upwardly facing recess seating the lower end of said conduit, a horizontally disposed holding plate for positioning the pump, spaced upstanding ribs on said plate opposing said member and disposed to space the lower end of the conduit from the plate so that the pump body may be readily inserted below the lower end of the conduit, there being elongated elements on said member extending lengthwise of said concavity adjacent said ribs to hold the distributor from twisting on said member as the distributor and pump are moved into and out of the box.

3. Structure as described in claim 2 in which the ribs have upstanding projections spaced longitudinally of the concavity and opposing the transverse member on the conduit to limit movement of the conduit and pump longitudinally of the concavity.

4. In a journal lubricator for a railway vehicle journal box, a distributor having a journal engaging body and a downwardly extending conduit and having an elongated element extending trans-

versely thereof at the lower end of said conduit with its ends offset downwardly, a pump including a body having a portion receiving the lower end of said conduit, springs compressed between said element ends and the body of the distributor, a horizontal plate having means to position said pump and having spaced upstanding ribs for engaging the ends of said element when the pump is removed and spacing the lower end of the conduit from the plate so that the pump body may be readily inserted below the lower end of the conduit.

5. In a lubricator for application to a railway vehicle journal box, a holding plate adapted to be seated on the bottom of the box and having front and rear ends and a central recess opening inwardly from said front end, spaced upstanding ribs on said plate extending longitudinally of the plate, each of said ribs being inclined upwardly and rearwardly from the front of the plate, then 15 downwardly and rearwardly and then substantially horizontally rearwardly, a pump movable into and out of said recess through the open end

of the latter and having an upwardly facing socket, a lubricant distributor with a journal engaging pad and a conduit depending therefrom and provided with a terminal movable vertically relative to the pad and arranged to be seated in said pump socket, there being a spring thrusting said pad and terminal apart, and a member extending laterally from said terminal and over said ribs.
